UNITED STATES PATENT OFFICE

HOWARD B. KEATH, OF RICHMOND HEIGHTS, MISSOURI, ASSIGNOR TO WAGNER ELECTRIC CORPORATION, OF ST. LOUIS, MISSOURI, A CORPORATION OF DELAWARE

AIR COOLED TRANSFORMER

Application filed April 18, 1931. Serial No. 531,141.

My invention relates to the cooling of electrical apparatus and has special reference to transformers which are enclosed in a liquid containing tank. Such tanks are generally made either with plain or corrugated surfaces with external radiating tubes connected to the top and bottom thereof to allow for a more rapid dissipation of heat from the liquid. The heated liquid, generally oil, rises to the top of the tank and passes into the upper part of the tubes and as the liquid dissipates its heat through the walls of the tubes into the surrounding air it will flow downwardly through the tubes to the bottom of the tank. The radiating surface of the tubes generally is not large enough to dissipate the heat from the fluid as rapidly as desired and it is the practice to subject the surfaces of tubes to currents of air. One of the objects of my invention is to provide an improved method of circulating air currents over the radiating tubes and tank to increase their radiating efficiency.

Another object of my invention is to subject the radiating tubes of a transformer tank to a maximum of cooling air by the use of a minimum amount of forced air.

Still another object of my invention is to produce an efficient cooling system for a transformer without increasing the over-all dimension of the liquid containing tank and the radiator tubes and one which can be readily placed on existing types of transformer tanks without in any way changing their construction.

Reference is now made to the drawings in which Figure 1 is a side view, partially in section, disclosing the invention applied to a transformer tank with external radiating tubes; and Figure 2 is a front view of one of the banks of radiating tubes showing how the air circulating means is attached.

The numeral 1 designates a rectangular-shaped tank of suitable dimensions in which is placed a transformer 2 immersed in an insulating fluid,—oil in this instance. The top of the tank is closed by a cover 3 which carries the electrical leads for the transformer winding. On opposite sides of the tank and spaced therefrom is a bank of radiating tubes

4 which consists of two rows of spaced apart elliptical-shaped tubes 5 terminating in headers 6 and 7 at the ends thereof. These headers are connected to the interior of the tank by means of tubes 8 having flanges 9 at one end for attachment to the wall of the tank by any suitable means. The heated oil in the tank circulates from the top of the tank to the bottom through the tubes 5 and is thereby cooled by the surrounding air. Other banks of tubes may be placed on the other sides of the tank if it is so desired.

To increase the efficiency of the radiating tubes it is desirable to subject their surfaces to a continuous current of cool air. This current of cool air serves the two-fold purpose of carrying the heated air away from the tubes and of bringing the cool air into contact with the tubes. It is also desirable to have these currents of air pass over the tubes at an acute angle thereto so as to assist the heated air about the tubes to rise.

In accordance with my invention I attach a blower to the bank of tubes below the lower header in such a way that a continuous blast or column of air will be directed vertically upward into the space between the tank and the tubes. This column of air in moving vertically upward causes currents of air to pass between and around the radiating tubes, as shown by the arrows in Figure 1, and also along the wall of the tank, resulting in the wall and the entire radiating surface of the tubes being subjected at all times to moving air. Since the air from the blower and the currents of air passing over the tubes are always moving upwardly, the heat radiated by the tank and the tubes is rapidly moved away from the radiating surfaces.

Tests have shown that this method of cooling the tank and radiating tubes of a transformer is approximately fifty per cent more effective than where the air is blown only directly upon the radiating tubes at right angles thereto with no provision for carrying the heated air upwardly and away from the tubes.

The embodiment of my invention shown consists of an air conduit 10 suspended from the bank of tubes by means of a strap 11 overlying the header member 7 between the rows 100

of tubes and connected by bolts 12 at its ends to brackets 13 fixed to the sides of the air conduit. The small end of the air conduit is formed in two outlet ports 14 and 15 so as 5 to fit around the connecting tube 8. Both of these outlets are curved and extend vertically upwardly into the lower part of the space between the wall of the tank and the bank of radiating tubes. In the main body 10 of the air conduit 10 is placed a blower comprising an electric motor 16 and a fan 17, the fan being adjacent the circular opening 18 in the end of the air conduit. One side of the air conduit is provided with a door 19 10 for inspection and repair of the motor and fan.

If it is necessary to have two fans to provide a sufficient continuous blast of air through the outlets 14 and 15, they may be 20 placed in the air conduit directly opposite the outlets in a manner similar to the mounting of the one shown but with separate openings 18 therefor.

From the foregoing description it is apparent 25 that I have produced a very efficient means for cooling a transformer tank which can easily and readily be attached to existing constructions and without increasing the over-all dimensions thereof.

Having fully described my invention, what I claim as new and desire to secure by Letters Patent of the United States is:

1. The combination of a fluid containing 30 tank for a transformer, a tank of spaced apart external radiating tubes connected to the top and bottom of the tank and spaced therefrom and through which the fluid circulates, and means for directing a continuous blast of air between the bank of tubes 40 and the tank and parallel to the tank, whereby air from the surrounding body of air will be drawn between the tubes at an acute angle thereto.

2. In combination with a liquid containing 45 tank for a transformer having a bank of vertical radiating tubes spaced from each other and from the tank and through which the liquid circulates, of a blower beneath the tubes, and means for directing the air from 50 the blower vertically upward into the space between the bank of tubes and the tank.

3. The combination with a fluid containing 55 tank having a plurality of external radiating tubes spaced from the tank and from each other and through which the fluid circulates, an air conduit extending into the lower part of the space between the tank and the tubes and positioned to discharge air in a direction parallel to the tubes, and a blower 60 in said conduit.

In testimony whereof, I hereunto affix my signature, this 14th day of April, 1931.

HOWARD B. KEATH.
